UNITED STATES PATENT OFFICE.

LEWIS J. TETLOW, OF HOLYOKE, MASSACHUSETTS.

TROLLEY-WHEEL CONSTRUCTION.

Application filed March 14, 1924. Serial No. 699,245.

To all whom it may concern:

Be it known that I, LEWIS J. TETLOW, a citizen of the United States, residing at Holyoke, in the county of Hampden and State of Massachusetts, have invented new and useful Improvements in Trolley-Wheel Construction, of which the following is a specification.

This invention relates to improvements in trolley wheels and trolley harp construction. An object of the invention is to provide a mounting for a trolley wheel so that it will run a long time without being relubricated. At the present time, experience shows that trolley wheels as now constructed, and mounted, run for only a few days before they are discarded and a new wheel substituted.

Broadly, the mounting of my improved trolley wheel comprises a fixed shaft which is supported in the trolley harp, which shaft passes through the hub portion of the wheel that is formed with a large internally located recessed portion, and, located in the recessed portion are a plurality or series of disks that are placed in staggered or overlapping positions relative to each other. Each of said disks are formed with several arc or segmental shaped portions which rest directly upon the fixed shaft. Alternately arranged with reference to the arc shaped bearing portions of the disks are recess or pocket portions for the purpose of receiving a suitable lubricant such as finely divided graphite that is mixed with a suitable binder element which possesses lubricating and electrical conducting properties. These recess portions communicate with the shaft receiving opening in the disk, whereby the lubricant will flow directly out of the recess portions and onto the shaft. The lubricant that is inserted in the recess portions is composed of a substance that readily conducts the electric current whereby the efficiency and life of the trolley wheel is materially increased both as to its wear and electrical conductivity. The construction and arrangement being such that when the wheel and its supporting shaft are assembled, it is practically impossible for the lubricant in the interior of the wheel to escape.

A further object of the invention is to provide a trolley harp for supporting the wheel and so constructed that the electric current will readily pass from the wheel to

the harp. Broadly, the harp comprises the usual spaced arm or fork portions in which the fixed wheel supporting shaft is located, and, oppositely disposed spring actuated contact members that engage and bear directly on the opposite sides of the trolley wheel and with means for varying the pressure of the spring actuated contact members against the opposite sides of the wheel, and at the same time, permitting the springs to have lateral or axial movement on the wheel supporting shaft.

A further object of the invention, which may be considered a modification, is to provide a detachable hub which may be readily inserted into and removed from the rim portion of the wheel, should occasion require such change. The hub being provided with the series of wheel supporting disks that are arranged in staggered relation to each other and each formed with recesses or pocket portions to receive the lubricating and the electricity conducting material. These and other objects will appear in the body of the specifications which will be clearly pointed out in the claims.

Referring to the drawings:

Fig. 1 is a side elevational view showing the complete wheel and the screws for retaining the disks and the closure plate in place.

Fig. 2 is a vertical sectional view substantially on the line 2-2 of Fig. 1 illustrating the interior construction of the wheel and showing the plurality of shaft supporting and lubricant retaining disks assembled in overlapping relation, also the spacing rings which operate to provide a cushion effect axially of the wheel and a closure plate for retaining disks in place.

Fig. 3 is a view similar to Fig. 2 showing the enlarged interior recessed portion of the wheel with the series of disks and rings and closure plate removed.

Fig. 4 shows the series of shaft supporting and lubricant retaining disks, the spacing rings, and the closure plate removed from the wheel, and separated from each other.

Fig. 5 illustrates one of the disks which is located in the recessed portion of the wheel and formed with lubricant receiving pockets or recesses and the openings for receiving the securing bolts.

Fig. 6 is a view similar to Fig. 5 but showing the recesses or lubricant retaining

pockets which are in different angular positions.

Fig. 7 is an elevational view of the end closure plate for closing the recess in the 5 side of the wheel as shown in Fig. 1.

Fig. 8 is a detail view of one of the compressible and spacing rings.

Fig. 9 is a transverse sectional view on the line 9—9 of Fig. 8 showing the interior 10 of the spacing ring which is filled with asbestos fibres.

Fig. 10 is a side elevational view of the assembled trolley harp and wheel.

Fig. 11 is a vertical sectional view on the line 11—11 of Fig. 10 showing the manner 15 of supporting the spring actuated contact brushes which normally bear against the opposite sides of the wheel, also the manner of normally exerting a spring pressure on 20 the brushes.

Fig. 12 is a detail view of the brush construction of the harp shown in detached and separated relations.

Fig. 13 is a side elevational view in which 25 the hub portion is made removable from the rim portion.

Fig. 14 is a vertical sectional view on the line 14—14 of Fig. 13 showing the interior construction of the removable hub and the 30 manner of attaching this hub to the spoke portions of the wheel.

Fig. 15 is a detail sectional view of the removable hub showing the recessed interior portion and the spoke parts formed with 35 openings to receive the securing bolts.

Fig. 16 is an end elevational view of the hub removed from the wheel.

Fig. 17 is a detail view of the supporting pin showing the oil retaining recesses therein, and 40

Fig. 18 is a plan view showing two of the disks in overlapping position, and

Figs. 19 and 20 are details of supporting the brushes.

45 Referring to the drawings in detail:

1 designates the trolley wheel as a whole which is formed with the usual annular groove 2 which receives and bears against the overhead trolley wire. The center or hub portion of the wheel is formed with an enlarged cored out recess 3 and an opening 4 through which the supporting shaft 5 passes. The hub portion is formed with three equally spaced openings 6 (see Fig. 1) 50 for receiving the threaded screws 7, for retaining the disks and cover plate in place. Located within the recess 3 are the disks 8, 9, 10, 11, and 12. 20 designates three spacing and compression rings that are arranged between the disks 8 and 9, 10 and 11, 55 and 12 and the end closure plate 14 as shown in Fig. 2. This end closure plate is formed with three threaded openings 15 for receiving the threaded ends of the bolts 7, 60 and 16 as shown in Fig. 2. Each of the disks 8, 9,

10, 11, and 12 are formed with correspondingly located openings 16 through which passes the retaining screws 7. Each of the disks is formed with an opening 17 having the spaced arc shaped portions 18 which rest directly on the shaft 5. Communicating with the openings 17 are the recesses or pockets 19 for receiving a lubricating substance. Since the arc shaped portions 18 rest directly upon the pin 5, as shown in 70 Fig. 2, the disks therefore support the wheel 1.

The recesses 19 are for the purpose of receiving the lubricant for the wheel, and, since these recesses are arranged in different 75 angular positions as comparison of the views in Figs. 5, 6, and 18 will readily show, the lubricant will therefore be pocketed or retained by reason of the overlapping or staggered relation of the recesses 19 in the 80 disks, when they are assembled. For the purpose of spacing some of the disks from each other to permit the lubricant to escape and for furnishing a more or less elastic 85 compressible, or cushion effect to permit the disks to slightly yield or move axially on the shaft 5 so that the cover plate 14 will seat firmly the three rings 20 are provided. A sectional detail of one of the rings is 90 shown in Fig. 9. These rings are preferably 95 formed of thin copper and folded as shown to confine the asbestos fibres 21 therein, whereby this material will slightly yield or bend when the wheel is operated.

After the disks 8, 9, 10, 11, and 12 and 100 the rings 20 are assembled, as shown in Fig. 2, the threaded screws 7 are inserted and passed through the openings 16 of the disks and threaded into the closure plate 14, which plate firmly seats on the annular 105 ledge 22, by reason of the yielding nature of the rings 20. After the disks are assembled suitable means are provided for completely filling the interior of the wheel with 110 a suitable lubricant, which filling operation is preferably carried out by inserting the end of a pump in the opening 4 and forcing the lubricant under high pressure and in a melted or semi-liquid condition, whereby 115 the lubricant will be driven into the pockets or spaces 19 and into the spaces around the rings 20 and at the edge of the disks in the annular space 23. The space 23 also serves the purpose of permitting the disks to swell or expand should they for any reason increase in size from absorbing the lubricant. 120

This lubricant is indicated at 24. After the parts are assembled and the lubricant is inserted the wheel is then placed in the trolley harp by inserting the pin 5. The pin 5 is retained in place by means of the cotter pins 25. The pin 5 is located in the arms 26 or yoke of the trolley harp. 125

For the purpose of forming a good electrical contact between the rotatable wheel 130

1 and the trolley harp, the spring actuated brushes 27 of bronze or copper are provided. These brushes are formed with an enlarged flat end portion 28 and an opening 29 to receive the pin 5. The flat end part 28 normally presses against the opposite ends 30 and 31 of the wheel, for collecting the current. The brushes 27 are of the shape shown in Figs. 11 and 12. Their lower ends are formed with a semi-circular recess 32 which seats or rests upon the washers 33 which washers are located in the recessed portion 34 of the arms 26, whereby the spring actuated brushes 27 are definitely located with relation to the pin 5. For the purpose of supplying a normal pressure on the brushes 27 to form a good electrical contact with the wheel 1 the curved springs 35 are provided; the lower ends of each of which is formed with an opening 36 through which passes the bolt 37. This bolt extends through an opening 38 in the arms 26. Located on the inner ends of each of these bolts is a lock washer 39. 40 25 designates a nut on each of the bolts 37, whereby suitable tension may be placed on the washers 39, which in turn, is transmitted to the spring arms 35. It should be stated that when the pin 5 is removed the brushes 27 may be readily withdrawn from their operative position on the arms 26 by simply pulling them lengthwise of the trolley harp. The brushes 27 and spring 35, it will be observed pass through the openings 26' of the arms 26.

For the purpose of preventing any oil or water from destroying the electrical contact between the brushes 27 and the arms 26, the two aprons 35' and 35² are provided 40 which would carry the oil or water away from the brushes which would destroy their electrical contact with the arms. Rivets 35³ are provided for attaching these aprons to the brushes 27.

45 In order to positively insure at all times, a good electrical contact between the brushes 27 and the arms, the recesses 34, see Figs. 11, 19 and 20, are formed with ridges 34' and grooves 34². The brushes 27 rest on the ridges 34' thus providing good electrical connection. The grooves 34² will serve the purpose to conduct or carry away any water or oil that might possibly collect under the brushes 27 and in the recesses. The two 55 end grooves 34² are extended through to the bottom of the harp as shown in Fig. 11.

Referring to the construction shown in Figs. 13 to 17 in which the trolley wheel 41 is formed with four inwardly or radially 60 projecting arms or spoke-like members 42 and 43 which are spaced from each other as shown in Fig. 14. The spaces between these arms is for the purpose of receiving the four radially arranged arms or spokes 65 44 of the removable hub member 45. This

removable hub member is formed with an enlarged cored out recess portion 3, the same as the hub part of the wheel 1, shown in Fig. 3, and located within this recess portion is the identical arrangement of the 70 disks 8, 9, 10, 11, and 12 and the closure plate 14. 46 is a pin that passes through the centrally arranged openings 17 in the disks and through the opening 47 of the hub member 45 which member is formed with 75 openings 48 for receiving the cotter pins 25 of the trolley harp shown in Fig. 11. The hub member 45 is formed with the spaced openings 49 for receiving and securing the screws 7 as already described. The 80 arms 44 are each formed with an opening 50 through which passes the securing bolts 51 shown in Fig. 14 whereby the arms 44 and the removable hub member 45 may be readily attached to and removed from the 85 wheel 41. The pin 46 is formed with grease retaining pockets 52 for the purpose of evenly distributing the lubricant thereon. It will be seen that when the hub member 90 45 and the supporting disks therein become worn that they may be readily removed by withdrawing the bolts 51 by giving it a slight rotary movement as indicated by the arrow 51', for removing the arms 44 from the space between the arms 42 and 43 and a 95 new hub member readily substituted for the worn one, or, if desired, the old one may be retained in the wheel 41 and refilled when new disks and rings and a new pin 46 is 100 inserted.

This form of wheel is particularly desirable for long distances or high speed traffic since the wheel 41 is made of larger diameter than the wheel 1.

The arc shaped surfaces 18 of the hard fibre disks 8, 9, 10, 11, and 12, it should be particularly observed, form the bearing surfaces for supporting the wheel 1 on the shaft 5. It should also be particularly observed that the pockets or recesses 19 in the fibre 105 disks provides a suitable means, or structure, for receiving the lubricating substance for the bearing surfaces 18, which rest directly on the shaft 5, and that the overlapping or staggered arrangement of the disks effectively confines and prevents the escape of the lubricant from the recess 3. It can flow or pass only through the narrow passageways 19' to the shaft 5.

110 It should be stated that the disks 8, 9, 10, 11, and 12 as shown in Fig. 4 are like those shown in Figs. 5 and 6, the broken lines 5—5 and 6—6, in Fig. 4, and the arrows thereon, indicate how the recesses 19 in these disks appear when assembled in overlapping relation. The same overlapping result may, of course be obtained by changing the positions of the openings 16 but leaving the angular positions of the recesses in the same 115 position in each disk. This is indicated in 120

Fig. 18 where the bolt receiving openings 16, in two overlapping disks register. The same result is accomplished by either method, that is to say, the lubricating and electrically 5 conducting substance is pocketed between the overlapping disks, as readily understood.

What I claim is:

1. In a trolley wheel construction, the combination with the hub portion which is 10 formed with a recess therein and an annular ledge part, a series of wheel supporting disks located in the recess, said disks each being formed with an opening to receive a wheel supporting shaft and having laterally located recesses communicating with the said opening to provide a space or pocket to receive a semi-solid lubricant, said lubricant possessing the property of readily conducting the electric current from the wheel to the 15 supporting shaft and means for securing the said disks in place in the recess comprising a plate located in the annular pan, and threaded screws passing through the disks, the plate and the hub.
2. A trolley wheel construction comprising in combination with an integral recessed hub portion thereof, a supporting shaft for the wheel, a plurality of fibre disks located within the said recessed portion and of less diameter than the recess of the hub, each disk having a shaft receiving and supporting opening, an arc shaped portion formed as a part of the disk that rests directly upon the supporting shaft and a recess which communicates with the said opening in the disk for receiving a suitable semi-solid lubricant that possesses the property of readily conducting electric current, and means including an end closure plate and screws passing 20 through the hub, plate and disks for securing the disks in place in the wheel.
3. A trolley wheel construction comprising in combination with a recessed hub portion thereof, a shaft for supporting the wheel, a plurality of disks located within the recessed hub portion, each disk having an opening to receive the shaft and an arc shaped portion that rests directly upon the supporting shaft, and a laterally arranged recess which communicates with the opening in the disk for receiving a suitable lubricant that possesses the property of readily conducting the electric current, means for securing the disks in place in the wheel, means for spacing the disks axially of the shaft.
4. In a trolley wheel, the combination with the hub portion thereof, which is formed with an open-ended recess, a closure plate for the open end, a supporting shaft extending through the hub and closure plate, a plurality of disks each formed with an opening and located in the recessed hub portion and engaging the shaft to form a bearing between the wheel and the shaft, spacing 60 rings located between the disks and the closure plate for permitting the disk to slightly yield axially on the shaft to permit the closure plate to firmly seat on the hub, as described.

5. In a trolley wheel, the combination with the hub portion thereof, which is formed with a recess and opened at one end, a closure plate for the open end, a supporting shaft extending through the hub and closure plate, a plurality of disks formed with 70 openings to receive the shaft and located in the recessed portion of the hub and engaging the shaft to form a bearing between the wheel and the shaft, spacing rings located between the disks and the closure plate 75 for permitting the disks to slightly move axially on the pin, when the closure plate is secured in place, each of the disks having pockets therein for receiving a lubricating substance and the pockets in the disks being 80 arranged in staggered relation to each other so that the pocket in one disk is closed by the adjacent disk, and the pockets having a passage way leading to the shaft to permit the lubricant to reach the shaft as the wheel 85 revolves.

6. A trolley wheel construction comprising a hub portion formed with a recess and openings therein, a shaft for supporting the wheel, a plurality of disks having openings and located in the recess and each formed with pockets for receiving a lubricant possessing electrical conducting property, the disks having passageways leading from the pockets to the shaft, the pockets 90 of the disks being arranged in staggered or overlapping relation for causing the pockets to be closed against lateral escape of the lubricant by its adjacent disk but permitting the supporting shaft to be lubricated, and 95 means for retaining the disks in the recess comprising a closure plate formed with screw threaded openings, threaded screws passed through closure plate, the openings 100 of the disks and the hub.

7. In a trolley wheel construction having a recessed hub and an annular seat formed thereon, a supporting shaft extending through the same, a plurality of disks located in the recessed part of the hub for 115 engaging the shaft, each of the disks having a pocket for receiving a shaft lubricating and electrical conducting substance, rings on the shaft and located between the disks, said rings being formed of compressible material, and means for securing the disks in place in the recess comprising a closure plate for engaging the annular seat and threaded bolts passing through the disks and closure plate, the construction and arrangement being such that when the securing bolts are operated the closure plate will be firmly seated on the annular seat.

8. A removable hub for trolley wheels, comprising, in combination, a one piece mem- 120

ber formed with an open ended recess having an annular seat portion, a closure plate for the opening and located on the seat portion, fibre disks in the recess of less diameter than the recess to permit expansion of the disks, each disk being formed with a shaft receiving opening, means for securing disks and closure plate together, and to the member, means for retaining a shaft lubricant between the disks.

9. A trolley wheel, comprising, in combination a recessed hub member, a supporting shaft, a plurality of shaft engaging disks in the recessed member, each disk being formed with a recess for receiving a shaft lubricating and electrical conducting substance and arranged with relation to each other so that the recesses in the disks do not register with each other for confining or pocketing the said substance in the recess, the disks having a passageway to permit the said substance to flow from the recess onto the shaft, means for securing the disks to the hub member, and means for removably securing the hub member to the rim part of the wheel.

10. A separable trolley wheel comprising in combination, a removable hub member, formed with a recessed portion, a supporting shaft, disks in the recessed portion which are formed with arc shaped parts that rest on the shaft, the diameter of the disks being less than the diameter of the recessed

portion to provide a free space for the disks to radially expand, a closure plate for the recessed portions, the hub member having an annular seat for the closure plate, rings between the disks, screws passed through the plate, hub member and disks to retain the disks in place and to draw the plate onto the annular seat, the disks being formed with recesses to receive a lubricating and electrical conducting substance.

11. A disk for the purpose described having a centrally disposed opening with arc shaped portions for engaging a supporting shaft when inserted in the opening, the opening having recessed portions with laterally extending portions between the arc shaped portions for receiving a lubricating substance for the shaft.

12. A support for a rotatable member, as a trolley wheel, comprising a plurality of disks, each formed with a shaft receiving opening the border of the opening having arc-shaped portions that engage the shaft, recesses in the disks between the said portions, each recess having laterally extending portions for receiving a lubricating substance, means for securing the disks together with the arc shaped portions and recesses in staggered or overlapping relation for retaining the lubricating material in the recesses but permitting it to lubricate the shaft.

LEWIS J. TETLOW.
